UNITED STATES PATENT OFFICE.

THEODORE H. NORTHRUP, OF DENVER, COLORADO, ASSIGNOR OF ONE-HALF TO FRANCIS E. PREWITT, OF DENVER, COLORADO.

DESIGN FOR A MUFF.

No. 40,169.

Specification for Design.

Patented July 20, 1909.

Application filed March 15, 1909. Serial No. 483,650. Term of patent 14 years.

To all whom it may concern:

Be it known that I, THEODORE H. NORTHRUP, citizen of the United States, residing in the city and county of Denver and State of Colorado, have invented a new, original, and ornamental Design for Muffs, reference being had to the accompanying drawing, which forms a part of this specification.

This invention relates to a new, original and ornamental design for muffs, the said design being illustrated in the accompanying drawing, which is an elevation of a muff, showing my new design.

What I claim is:

The ornamental design for a muff, as shown.

THEODORE H. NORTHRUP.
